UNITED STATES PATENT OFFICE.

CHARLES A. KIRKWOOD, OF CHICAGO, ILLINOIS.

DESIGN FOR A TOOTH POWDER AND BRUSH HOLDER.

SPECIFICATION forming part of Design No. 30,560, dated April 18, 1899.

Application filed March 18, 1899. Serial No. 709,693. Term of patent 7 years.

To all whom it may concern:

Be it known that I, CHARLES A. KIRKWOOD, a citizen of the United States, and a resident of Chicago, county of Cook, State of Illinois, have invented and produced a new and original Design for Tooth Powder and Brush Holders, of which the following is a description, reference being had to the accompanying drawings, which form a part of this application, and in which—

Figure 1 is a front elevation of my new design. Fig. 2 is a top plan view of the same, and Fig. 3 is an end elevation.

Referring to the drawings, it will be seen that my new design is in the form of a shelf and is composed of the back portion A, having its upper edge formed with a series of curves and with openings *aa* therein, tongues *ff*, extending therefrom, and with parallel vertical sides *bb*. From the bottom of the back portion extends at right angles thereto

a shelf B, in the front edge of which are formed several rectangular openings *c*. From the central portion of the shelf B extends a second shelf C, which is rectangular in outline and is approximately the same depth of the shelf B and about one-fourth of the length of said shelf. The sides of the shelves B and C are parallel, and the front edges *d* and *e* of said shelves have a slight upward turn, as clearly shown in Fig. 3.

Having thus described my new design, what I desire to secure by Letters Patent is—

The design for a tooth powder and brush holder, substantially as herein shown and described.

In testimony whereof I affix my signature in presence of two witnesses.

CHARLES A. KIRKWOOD.
